UNITED STATES PATENT OFFICE.

FELIX LOUISOT, OF NEW YORK, N. Y., ASSIGNOR TO VACUUM PULP PRODUCTS CORPORATION, OF NEW YORK, N. Y., A CORPORATION OF VIRGINIA.

PULP-MOLDING APPARATUS.

Application filed January 25, 1921, Serial No. 439,774. Renewed June 24, 1926.

This invention relates to the manufacture of dolls' heads or other articles out of wood pulp or the like.

The objects of the invention are to provide a machine of relatively simple construction which can be quickly and easily manipulated to produce the desired results.

Special features relate to the control of the pulp supply, the control of the suction 10 for forming the pulp deposit, the control of the compressed air for removing the excess moisture from the formed product and the method of freeing the product from the mold walls.

15 The machine disclosed herein is of the same general nature as the machines shown in my copending applications which have matured into Patents Nos. 1,527,200 to 1,527,203, inclusive, all of which issued on 20 February 24, 1925.

In the drawings accompanying and forming a part of this specification I have illustrated the invention embodied in a practical commercial form but wish it understood that 25 the structure may be modified in various ways without departure from the true spirit and scope of the invention as hereinafter defined and claimed.

20 In these drawings, Figure 1 is a vertical 30 sectional view of the apparatus, parts appearing in elevation.

Figure 2 is a plan view of the same.

Figure 3 is a vertical sectional view on a 35 plane at right angles to the plane of Figure 1, said view being taken on substantially the line 3—3 of Figure 2.

Figure 4 is a horizontal sectional view 40 across the mold chamber as taken on substantially the plane of line 4—4 of Figure 1.

Figure 5 is a perspective view of the 45 machine showing the bottom section of the mold lowered to open the mold chamber.

The pulp is supplied in the present disclosure from a gravity feed reservoir 7 45 which receives its supply from a suitable reservoir through a conduit 8 under control of a float valve 9.

Extending from the chamber 7 is a pulp 50 outlet 10 which forms a pulp supply conduit opening into the side of the mold chamber at 11, Figure 3.

12 designates the mold chamber, said

chamber having a neck 13 at its lower end to receive the close-fitting plug portion 14 of the mold bottom member 15. This mold 55 bottom is shown provided with outstanding perforated lugs 16 sliding over the upright guide rods 17, it being held in its uppermost position, closing the bottom of the mold chamber, by a rod 18, trunnioned at 19 in the lower ends of the guide rods and arranged when swung upward, as in Figures 1 and 3, to engage a cam or inclined shoulder 20 on the mold bottom. Adjustment for wear of the parts is provided by screw 65 threading the lower end of the mold closing rod into its trunnion piece 21 and securing it in adjusted position by lock nut 22.

The mold bottom carries on its upper face a perforated mold forming wall 23 conforming in shape to the inner face of the base portion of the molded article. In this particular instance the mold is shaped to form a doll's head and this base portion of the mold wall is therefore shaped to form 75 the inner surface of the shoulder portion of the doll head.

The mold bottom is also provided with an opening 24 in its side to register with the pulp inlet 11 in the side of the mold chamber (Figure 3) and with a tubular member 25 extending from said side opening 24 up through the mold wall 23, said member forming in effect, when the mold is closed, a continuation of the pulp conduit. To provide 80 a proper sealing of the mold chamber, a gasket 26 may be carried by the mold bottom to make sealing engagement with the mouth of the mold chamber.

The other walls of the mold are provided 85 in the present disclosure by the cooperating perforated side walls 27 and 28 which are shaped to form the front and back of the head and fit together over the top of the mold bottom when the mold is closed, as in 90 Figure 1. These mold sides are shown as carried by rods 29 sliding through stuffing boxes 30 in the walls of the mold chamber, said rods being carried by brackets 31 slidingly guided at their upper ends on a fixed 95 guide rod 32 and operated by screws 33 engaging in appropriate screw seats provided at 34 in the brackets and carried at the opposite ends of a rotary shaft 35 journaled

in suitable bearings on the top of the mold chamber.

To get a quick mold closing and opening operation I have shown the screw shaft 35 as provided with a pinion 36 in engagement with a spur gear 37 journaled on a bearing bushing 38 on the front of the mold chamber and surrounding the stuffing box of the forward mold rod 29, said gear having an outstanding handle 39 by which the same may be turned to effect the opening and closing movements of the mold sides.

The supply of pulp is controlled in the present disclosure by a 3-way valve 40 interposed in the pulp line 10 and operative to provide a through-way connection for the pulp, as in Figure 3, or when turned to the left in this figure, to permit the "backwash" or excess to drain back from the mold and out through a discharge or waste pipe 41.

Interposed in the pulp conduit in the present disclosure is another 3-way valve 42 which is operative in the position shown in Figure 3 to form part of the pulp supply conduit and adapted when turned to the right in this view to shut off connection with the pulp supply and connect the interior of the mold with a compressed air conduit 43.

39 A branch or by-pass 44 from this compressed air conduit opens into the side of the mold chamber, said by-pass being under control of a suitable valve 45.

In the arrangement shown in Figure 1 where the constant level supply tank is on a level or slightly above the level of the mold, a gravity flow may be depended on to fill the mold. This could be accomplished by simply opening the pulp supply valve 40 and permitting the pulp to fill the mold chamber. Usually, however, the charging of the mold is assisted by applying suction to the chamber enclosing the mold and thus in effect "drawing" the pulp positively and 45 somewhat forcibly into the mold. For this purpose I have shown a suction conduit 46 connected with the bottom of the mold containing chamber, and controlled by a suitable valve 47. Also, in the present disclosure 50 there is provided a suction conduit 48 connected with the top of the mold chamber and controlled by valve 49. About this control valve there is provided a by-pass 50 governed by a valve 51.

55 In order that the operation may be observed I have provided a sight glass or window 52 in one side of the mold chamber and have shown an illuminating device such as an electric lamp 53, let into the side of the mold chamber adjacent the window.

The molded product is separated from the mold walls by a series of "air shocks" produced by the operation of a so-called "fluter valve" 54 controlling an opening 55 (Figure 3) in the top of the mold chamber

and normally held to its seat by a spring 56 bearing against the under side of a lever 57 pivoted at 58 on top of the mold chamber and tensioned by a screw 59 bearing on top of the mold chamber.

Operation.

The mold is closed by elevating the mold bottom and turning the handle 39 to bring the mold sides together over the top of the same. The pulp is then admitted to the interior of the mold by opening valve 40 to the pulp supply, as in Figure 3, and if suction is used to assist in the filling of the mold, either the valve 47 in the suction conduit 46 which enters the bottom of the mold chamber is opened or suction is applied at the top of the mold chamber by opening valve 49 or the by-pass valve 51. This latter valve is used where it is desired to apply only a small suction force and this is done particularly when it is wished to fill the mold chamber gradually and without sudden shock. When the mold is filled and a sufficient initial deposit of pulp is produced on the mold walls, the pulp valve 40 is turned (left-handedly in Figure 3) to permit the excess or "backwash" to flow from inside the mold out the waste pipe 41.

When suction is employed to assist in the formation of this initial deposit, the valves 47, 49 and 51 will be controlled according to the effect which it is desired to produce. If a heavy initial deposit is desired and the pulp is of a character which will permit of such treatment, either the valve 47 or the valve 49, or both, may be opened to apply the full suction to the outside of the mold. This naturally produces a quick and sudden filling of the mold. If on the other hand circumstances require that the mold be filled relatively slowly, and the deposit be formed gradually, the by-pass valve 51 is used to apply a reduced or slower acting suction to the outside of the mold.

After the building up of a pulp wall of sufficient thickness and the draining off of the backwash, the excess moisture in the molded pulp is removed by admitting compressed air inside the mold, this being accomplished in the illustration by turning the valve 42 in a right handed direction in Figure 3 so as to shut off connection with the pulp supply and open up this part of the pulp conduit with the compressed air in pipe 43. At this time the valve 47 in the suction conduit at the bottom of the mold chamber is preferably open so that the water forced out of the pulp and through the perforate mold wall will drain into the bottom of the mold chamber and be carried off through said suction conduit. To drain the moisture from inside the base of the molded product I have shown the mold bottom as having a transverse passage 60 from which braces 61

lead upward into the space beneath the bottom wall 23 of the mold, said transverse passage opening out through the cylindrical hub portion of the mold bottom and registering with perforations 62 provided for the purpose in the neck or socket 13 in the bottom of the mold chamber (Figures 1 and 4). This moisture expressing operation may be observed through the window in the side of the mold chamber and the operation be governed accordingly, the pressure being maintained or applied as long or as many times as may be found necessary to effect the best results.

The next step in the process is to give to the article the air shock or shocks required to properly free it from the mold walls. This is accomplished usually by opening valve 45 to admit compressed air into the chamber surrounding the mold, the flutter valve operating repeatedly as the pressure accumulates sufficiently to overcome the tension of the spring 56 to release such pressure and thereby produce a series of light "impacts" on the article within the mold, these impacts serving to free the pulp wall from the mold without in any way injuring it. The force of these impacts can be governed by regulating the pressure of the air and the opposing valve closing spring and by controlling the various valves in different ways.

The molded product is finally removed by turning the handle 39 in a direction to open the mold sides and by then lowering the mold bottom as in Figure 5, the molded product during this latter movement being supported by the mold bottom, from which it can be lifted and subjected to further drying or other operations.

What I claim is:

1. In apparatus of the character described, a mold chamber having an opening in the bottom thereof, a mold bottom insertable up through said opening, laterally movable mold sides arranged within the chamber and cooperating with the mold bottom when the latter is in its elevated position to form a complete mold, and means for operating the mold sides.
2. In apparatus of the character described, a mold chamber having an opening in the bottom thereof, a mold bottom insertable up through said opening, mold sides within the chamber and cooperating with the mold bottom in its elevated position to form a complete mold and means for operating the mold sides, including supporting rods working through opposite sides of the mold chamber, brackets connected with the outer ends of said rods and provided with screw seats and a rotary shaft carrying screws in engagement with said screw seats.
3. In apparatus of the character described, a mold chamber having an opening in the bottom thereof, a mold bottom insertable up

through said opening, mold sides within the chamber and cooperating with the mold bottom on its elevated position to form a complete mold and means for operating the mold sides, including supporting rods working through opposite sides of the mold chamber, brackets connected with the outer ends of said rods and provided with screw seats, a rotary shaft carrying screws in engagement with said screw seats, a pinion on said screw shaft and a gear in mesh with said pinion and provided with an operating handle.

4. In apparatus of the character described, a mold chamber having an opening in the bottom thereof, a mold bottom insertable up through said opening, mold sides within the chamber and cooperating with the mold bottom in its elevated position to form a complete mold and means for operating the mold sides, including supporting rods working through opposite sides of the mold chamber, brackets connected with the outer ends of said rods and provided with screw seats, a rotary shaft carrying screws in engagement with said screw seats, a pinion on said screw shaft and a gear in mesh with said pinion and provided with an operating handle, said gear being journaled on a support concentric to one of the mold side supporting rods.

5. In apparatus of the character described, a mold chamber having an opening in the bottom thereof, a mold bottom insertable up through said opening, mold sides within the chamber and cooperating with the mold bottom in its elevated position to form a complete mold, guide rods dependent from the mold chamber at opposite sides of the opening therein, guide lugs on the mold bottom sliding over said guide rods and means for securing the mold bottom in its upraised position.

6. In apparatus of the character described, a mold chamber having an opening in the bottom thereof, a mold bottom insertable up through said opening, mold sides within the chamber and cooperating with the mold bottom in its elevated position to form a complete mold, guide rods dependent from the mold chamber at opposite sides of the opening therein, guide lugs on the mold bottom sliding over said guide rods, means for securing the mold bottom in its upraised position, said means including a supporting rod trunnioned at its lower end to the guide rods and an inclined shoulder on the mold bottom positioned to be engaged by the upper end of the supporting rod when the same is swung upwardly.

7. In apparatus of the character described, a mold chamber having an opening in the bottom thereof, a mold bottom insertable up through said opening and mold sides within the chamber and cooperating with the mold bottom in its elevated position to form a complete mold, the mold bottom hav-

- ing a pulp supply passage extending from one side thereof upwardly into the mold space and the mold chamber having a pulp supply conduit to register with said passage.
8. In apparatus of the character described, a mold chamber having an opening in the bottom thereof, a mold bottom insertable up through said opening and mold sides within the chamber and cooperating with the mold bottom in its elevated position to form a complete mold, the mold chamber having a neck surrounding the opening in the bottom thereof and provided with a pulp inlet in one side and the mold bottom having a plug portion fitting closely in said neck and provided with a pulp passage open at one side to register with the pulp inlet and extending up through the top of the mold bottom.
- 10 9. In apparatus of the character described, a chamber having an opening in the bottom thereof and a pulp inlet in one side of said opening, a closure for the opening provided with an upwardly extending pulp conduit registering at its lower end with said inlet and a perforate mold within the chamber over the upper end of the pulp conduit.
- 15 10. In apparatus of the character described, a chamber having an opening in the bottom thereof and a pulp inlet in one side of said opening, a closure for the opening provided with an upwardly extending pulp conduit registering at its lower end with said inlet, a perforate mold within the chamber over the upper end of the pulp conduit and controllable means for applying suction and pressure to the mold containing chamber.
- 20 11. In apparatus of the character described, a chamber having an opening in the bottom thereof and a pulp inlet in one side of said opening, a closure for the opening provided with an upwardly extending pulp conduit registering at its lower end with said inlet, a perforate mold within the chamber over the upper end of the pulp conduit, controllable means for applying suction and pressure to the mold containing chamber and a yieldingly closed automatically opening pressure releasing valve on the mold containing chamber.
- 25 12. In a machine of the character described, a mold chamber provided with an opening, an inner mold wall carrying member insertable in said opening; a mold wall in the chamber cooperating with said member and controllable means for applying suction and pressure to the space within the chamber surrounding the mold.
- 30 13. In a machine of the character described, a mold chamber provided with a window in one side thereof, a perforate mold within said chamber and in view of said window, a pulp supply conduit to the interior of the mold and means for controlling pressure within the mold chamber.

14. In a machine of the character described, a mold chamber provided with a window in one side thereof, a perforate mold within said chamber and in view of said window, a pulp supply conduit to the interior of the mold, means for controlling pressure within the mold chamber, a pocket in one side of the mold chamber and an illuminating source in said pocket and arranged to direct its light onto the perforate mold within the chamber.
15. In a machine of the character described, a mold chamber, a two-part perforate mold within the chamber, supporting rods extending through opposite sides of the mold chamber into engagement with the parts of the mold, brackets connected with said rods and provided with screw seats, a rotary shaft supported on the mold chamber and having reversely running screws engaged with said screw seats and quick operating means for turning said screw shaft.
16. In a machine of the character described, a mold chamber, a spring tensioned flutter valve controlling escape of pressure from said chamber, a perforate mold within the chamber, means for supplying pulp to the interior of said mold and means for controlling pressure in the mold chamber and within and without the mold therein.
17. In a machine of the character described, a mold chamber, a spring tensioned flutter valve controlling escape of pressure from said chamber, a perforate mold within the chamber, means for supplying pulp to the interior of said mold, means for controlling pressure in the mold chamber and within and without the mold therein and means for regulating the tension of the flutter valve.
18. In a machine of the character described, a mold chamber, a perforate mold within said chamber, a pulp supply conduit opening into said mold and provided with a backwash outlet, a 3-way valve at said outlet for controlling flow of pulp into the mold and the release of backwash from the mold, a pressure connection with the pulp conduit at a point between the mold and said valve, valve mechanism at the junction of said pressure connection with the pulp conduit and a controllable by-pass about said last mentioned valve.
19. In a machine of the character described, a mold chamber, a perforate mold within said chamber, a pulp supply conduit opening into said mold and provided with a backwash outlet, a 3-way valve at said outlet for controlling flow of pulp into the mold and the release of backwash from the mold, a pressure connection with the pulp conduit at a point between the mold and said valve, valve mechanism at the junction of said pressure connection with the

- pulp conduit and a controllable by-pass about said last mentioned valve, said by-pass extending from the pressure supply into the mold chamber outside the mold.
- 5 20. In a machine of the character described, a perforate mold, a pulp supply conduit opening thereinto, a compressed air connection to said conduit, valve mechanism at the junction of said pressure connection with said conduit for controlling flow of either pulp, compressed air or both into the interior of the mold, a chamber about the perforate mold and a regulatable by-pass about the valve mechanism and extending from the pressure connection to the mold chamber outside the mold.
- 10 21. In a machine of the character described, a mold chamber, a hollow perforate mold wall supported therein, means for supplying pulp to the interior of said hollow mold wall and a drainage passage from the interior of said hollow perforate mold wall to the interior of the mold chamber.
- 15 22. In a machine of the character described, a mold chamber, a hollow perforate mold wall supported therein, means for supplying pulp to the interior of said hollow mold wall, a drainage passage from the interior of said hollow perforate mold wall to the interior of the mold chamber, a perforate mold wall overstanding and spaced from said first mold wall and means for applying suction to the mold chamber.
- 20 23. In a machine of the character described, a mold chamber having a tubular neck provided with an opening in one side, a removable plug fitting in said neck and provided with a passage to register with said opening, a hollow perforate mold wall carried by the plug and a drainage passage extending from the interior of said hollow mold wall to the first passage.
- 25 24. In a machine of the character described, a mold chamber having a neck provided with openings in the sides thereof, a plug for closing said neck having a transverse passage to register at its opposite ends with the openings aforesaid, said transverse passage having a branch or branches opening to the end of the plug and a perforate mold wall over said branch or branches.
- 30 25. In a machine of the character described, a mold chamber having a neck provided with openings in the sides thereof, a plug for closing said neck having a transverse passage to register at its opposite ends with the openings aforesaid, said transverse passage having a branch or branches opening to the end of the plug, a perforate mold wall over said branch or branches and a pulp supply conduit in the plug extending through the hollow perforate mold wall.
- 35 26. In a machine of the character described, a mold chamber having a neck provided with openings in the sides thereof, a plug for closing said neck having a transverse passage to register at its opposite ends with the openings aforesaid, said transverse passage having a branch or branches opening to the end of the plug, a perforate mold wall over said branch or branches and a pulp supply conduit in the plug extending through the hollow perforate mold wall, said pulp conduit opening to the side of the plug and the neck aforesaid having a pulp inlet to register with said side opening.
- 40 27. In a machine of the character described, a mold chamber having a neck provided with openings in the sides thereof, a plug for closing said neck having a transverse passage to register at its opposite ends with the openings aforesaid, said transverse passage having a branch or branches opening to the end of the plug, a perforate mold wall over said branch or branches, a pulp supply conduit in the plug extending through the hollow perforate mold wall, said pulp conduit opening to the side of the plug and the neck aforesaid having a pulp inlet to register with said side opening and a cooperating perforate mold wall in the mold chamber over said first mentioned mold wall.
- 45 28. In a machine of the character described, a mold chamber having a pulp inlet leading thereinto, a pulp supply pipe in communication with said inlet, a perforated mold within the chamber over the end of the pulp inlet, means for applying a pressure within the chamber to the exterior of the mold therein, and a pressure actuated valve adapted to periodically release the pressure within the chamber at predetermined intervals to free the molded article from the perforated mold.
- 50 29. In a machine of the character described, a mold chamber having a pulp inlet leading thereinto, a pulp supply pipe in communication with said inlet, a perforated mold within the chamber over the end of the pulp inlet, means for applying a pressure within the chamber to the exterior of the mold therein, a pressure actuated valve adapted to periodically release the pressure within the chamber at predetermined intervals to free the molded article from the perforated mold and means for tensioning said pressure actuated valve.
- 55 60. In testimony whereof I affix my signature.

FELIX LOUISOT.
